UNITED STATES PATENT OFFICE.

COSTER J. MACK, OF YONKERS, NEW YORK, ASSIGNOR TO OTIS ELEVATOR COMPANY, OF JERSEY CITY, NEW JERSEY, A CORPORATION OF NEW JERSEY.

SAFETY ATTACHMENT FOR PUNCH-PRESSES.

1,113,026.

Specification of Letters Patent.

Patented Oct. 6, 1914.

Application filed August 26, 1912. Serial No. 716,965.

To all whom it may concern:

Be it known that I, COSTER J. MACK, a citizen of the United States, residing at Yonkers, in the county of Westchester and 5 State of New York, have invented a new and useful Improvement in Safety Attachments for Punch-Presses, of which the following is a specification.

My invention relates to safety attachments 10 for punch presses and similar machines.

An object of the invention is to provide means which shall act positively to remove the operator's hands from a position between the die plates in case the machine is operated while his hands are in such position.

In the accompanying drawings which illustrate an embodiment of my invention, Figure 1 is a view showing my safety device attached to a punch press; Fig. 2 is a view 20 on a somewhat larger scale of the safety device; Figs. 3 and 4 are detail views on a still larger scale of links used in the construction of the safety device.

In order to illustrate the principle of operation of my invention, I have shown the 25 same in Fig. 1 applied to a punch press A. It will be understood of course that the invention is applicable to a large variety of machines of this general class. The press 30 A as herein shown comprises a frame 1 in which is journaled a shaft 2 formed with an eccentric 3. A drive wheel or pulley 4 is attached to the shaft 3. The material to be operated upon, such as sheet metal, is fed 35 between the upper and lower dies 5 and 6. During each operation of the press, the shaft 2 is given one complete revolution to carry the upper die or punch downward and then return it to a position of rest. In order to 40 properly position the material between the dies, the operator is required to have his hands between the dies after each operation of the press, and if the machine is accidentally operated before his hands are removed, it 45 often results in a serious accident. In order to prevent such an occurrence, I have provided an attachment which operates positively to force the operator's hands to a position of safety in the event of the punch 50 descending before his hands have been withdrawn from beneath the punch. This device is in the form of a lazy-tongs carrying on its opposite ends a pair of shields. The lazy-tongs comprises two pairs of links 7 connected by pivots 8, and short links 9, pivoted

to the ends of the links 7. The short links 9 are pivotally connected at their outer ends to shields 10. Each shield 10 is in the form of a curved arm carrying at its lower end a roller 11. Rollers 12 are provided on the 60 links 9 to hold the shields 10 in a substantially vertical position. The safety device is attached to the lower die plate by means of an angle bracket 13 having a pivotal connection with one of the pivot pins 8. The 65 device is attached to the upper die plate by means of a link 14 pivotally connected at its lower end to the links 7. The link 14 is provided with a vertical slot 15. Pins 16 arranged in vertical alinement extend 70 through the slot 15 and are secured to the upper die plate. This construction permits a vertical movement of the link 14 relative to the die plate. A coil spring 17 preferably connected between two of the central 75 pivot pins 8 as shown, is normally under tension. The shields 10 are preferably provided with a facing 18 of leather or other suitable material secured in place by means of rivets 19.

The operation of the device is as follows: When the press is in its normal position of rest with the upper die lifted, the arms or shields 10 are drawn inwardly and are in position to permit the operator to place the 85 punching material in position or to perform any other necessary operation requiring the use of his hands between the dies. When the press is operated causing the punch to descend, the link 14 is carried downward 90 and operates the lazy-tongs to force the arms 10 outward in a lateral direction. The operator's hands and arms are thereby forced to a position of safety in case they have not already been removed before the 95 press is operated. As the upper die is lifted the pins 16 which extend through the slot 15 are carried upward permitting the spring 17 to draw the arms 10 inward to their initial position. The purpose of this slot-and-pin connection co-operating with the spring 17, is to permit a yielding inward movement of the shields so that in the event of the operator having his hands or fingers 100 between the links 7 and 9 while the safety device is extended they will not be pinched as the upper die is lifted. In other words the arms 10 are drawn inward only with a yielding pressure due to the spring 17, whereas they are forced outwardly with a 105 110

positive pressure transmitted from the descending die plate. The rollers 11 travel on the lower die plate or platform during the operation of the safety device.

5. It will be understood that various modifications of the structure herein disclosed might be employed without departing from the spirit of the present invention. The invention comprehends such modifications as 10 come within the scope of the appended claims.

What I claim is:—

15. 1. The combination of a press machine comprising relatively movable plates, a safety attachment comprising a lazy tongs and guards at the ends thereof, connections between said plates and lazy tongs to extend the latter as the plates are moved toward each other, and means to retract the lazy 20 tongs with a yielding force as the plates are separated.

25. 2. The combination of a punch press comprising a lower plate, an upper plate movable toward and from the lower plate, guards, a lazy tongs connecting the guards, a pivotal connection between the lazy tongs and the lower plate, a slot and pin connection between the lazy tongs and the upper plate, and a spring placed under tension by the extension of the lazy tongs.

30. 3. As an article of manufacture, a safety device comprising a lazy tongs, shields or guards pivoted to the ends of the lazy tongs, and stop devices to limit the pivotal movement of the guards.

35. 4. The combination of a lazy tongs, arms pivoted thereto, means to limit the rotation

of said arms, and guide rollers carried by the arms.

5. In combination, a lazy tongs, guards 40 connected to the ends of the lazy tongs, a slotted link connected to the lazy tongs, and a coil spring connected to and forming a means for retracting the lazy tongs.

6. The combination of a machine comprising members relatively movable toward and from each other, guards or shields extending across the space between said members, a lazy tongs connecting said guards or shields and operable to move said guards or 50 shields in opposite directions as one of said members is moved toward the other, and guide rollers carried by said guards or shields.

7. The combination of a machine comprising members relatively movable toward and from each other, guards or shields extending across the space between said members, a lazy tongs connecting said guards or shields and operable to move said guards or 55 shields in opposite directions as one of said members is moved toward the other, a lost motion connection between said lazy tongs and one of said members, and a spring adapted normally to take up the lost motion 60 in said connection.

In testimony whereof, I have signed my name to this specification in the presence of two subscribing witnesses.

COSTER J. MACK.
